STRING MUSICAL INSTRUMENT

Filed March 5, 1928

WITNESS:

Leonard Dodson and
James Dodson
INVENTORS
BY Victor J. Evans

ATTORNEY

UNITED STATES PATENT OFFICE

LEONARD DODSON AND JAMES DODSON, OF CHICAGO, ILLINOIS

STRING MUSICAL INSTRUMENT

Application filed March 5, 1928. Serial No. 259,234.

This invention relates to certain novel improvements in string musical instruments and has for its principal object the provision of an improved construction of this character which will be highly efficient in use and economical in manufacture.

Another object of our invention is to provide a string musical instrument of the character disclosed in our co-pending application, 10 Serial No. 228,415, filed in the United States Patent Office on or about October 24, 1927, which will embody an improved construction wherein it will be possible to obtain half notes or as they are called, chromatic notes.

15 A further object of the invention is to provide an improved mounting stud to which the strings may be connected and which will be arranged such that the strings for the full and half tones may be attached thereto in
20 a manner well understood in the art.

Other objects will appear hereinafter.

The invention consists in the novel combination and arrangement of parts to be hereinafter described and claimed.

25 The invention will be best understood by reference to the accompanying drawings, showing the preferred form of construction and in which:

Fig. 1 is a plan view of an instrument embodying a preferred form of construction for our invention;

Fig. 2 is a side elevational view of the device as illustrated in Fig. 1;

Fig. 3 is a perspective detail view depicting the preferred form of construction for the mounting stud we employ in our device showing said stud in operative position with the string attached thereto;

Fig. 4 is a perspective detail view of the
40 mounting stud showing said stud in unas-
sembled position;

Fig. 5 is a perspective detail view depicting the manner in which the string is formed prior to being assembled on the device; and

45 Fig. 6 is a fragmental detail view substantially similar to Fig. 2 showing a modified form of construction for my device.

50 In the drawings, wherein we have illustrated a preferred embodiment of our invention, 10 indicates a sound box which may be

formed in any desired shape or style. Mounted on the upper side of the sound box 10 adjacent one edge thereof are frets 11 and 12 which are disposed in spaced relation to the ends of the sound box. Disposed between the fret 11 and the juxtaposed end of the sound box, are a plurality of anchoring studs 13. Disposed between the fret 12 and the juxtaposed end of the sound box 10 is another group of anchoring studs indicated by 14. The studs 13 and 14 are adapted to be arranged in groups in order that the strings 15 which are adapted to be stretched therebetween may be arranged in groups in the manner disclosed in Fig. 1, and these groups of strings embody a note formation such that when they are manipulated they will produce harmonizing chords to a melody being played on the strings which are mounted in a manner now to be described.

anchoring studs 20 is a fret 21. Mounted on the side of the member 16 is a group of adjustable anchoring studs 22 which are disposed substantially in alignment with the anchoring studs 20 and mounted on the side of the member 17 are a plurality of anchoring studs 23 which are also disposed substantially in alignment with the anchoring studs 20.

As is best illustrated in Fig. 4 the studs 18 are screw threaded at the lower end thereof as indicated at 24 and these studs are adapted to be screw threadedly mounted in openings in the members 16 and 17. In the extent of the member 18 and in juxtaposition to the upper end of the screw threads 24 an upwardly inclined opening 25 is provided which extends through the stud 18. On the side of the stud 18 opposite the lower-most end of the opening 25 and disposed so as to lie in a plane below the plane of said opening, a groove 26 is formed. The upper portion of the stud 18 is preferably tapered upwardly, said taper being arranged so that the widest portion thereof is disposed in the region of the opening 25. The sides of the stud 18 are fluted in the portions into which the opening 25 opens and this fluted arrangement is preferably arranged such that it increases in width toward the upper side of the stud 18. In the upper end of the stud 18, two notches or grooves 27 and 28 are provided. On the upper side of the members 16 and 17 in the region in which the studs 18 are to be mounted, guide strips such as that indicated by 29 in the drawings, are provided which embody openings therein which are spaced apart predetermined distances and through which the studs 18 are adapted to extend. These guide strips are adapted to bear indicia which are to instruct a novice in playing the device inasmuch as they are marked to denote the note of the scale and if desired, other guide indicia may be provided thereon.

In Fig. 5 we have illustrated the formation of the string which we employ in our device and which is indicated by 30. As is clearly shown in Fig. 5 the string 30 is preferably U-shaped and when said string is disposed in operative position the bight portion 31 thereof is mounted in the notch 26 in the stud 18. The branch portions of the string are then led around the stud 18 and are then directed through the opening 25. The strings are then led up along through one of the fluted portions in the stud 18 and then are individually directed through the notches 27 and 28. One of the portions of the strips is directed to the proper one of the anchoring studs 20 and the other of the strings is directed to the proper one of the anchoring studs 22 or 23. A fret 32 is provided adjacent the anchoring studs 22 and a fret 33 is disposed adjacent the anchoring studs 23 and

it is apparent that the portion of the string led to these anchoring studs will be directed over these frets. The portion of the string led to the anchoring studs 20 will be directed over the fret 21. After the strings have been mounted individually in the studs 18, the strings are tuned in the manner well understood in the art, the strings extending between the studs 18 and 20 being tuned to the full notes and the strings extending between the studs 18 and 22 and 23 being tuned to the half notes. As is well understood in the art, certain of the notes of the diatonic scale do not harmonize properly with the half notes and these particular notes are arranged so as to embody only one string, that is, the string is arranged so as to embody only one branch portion. This single string is mounted in a manner substantially similar to the foregoing, the difference residing in the fact that the branch portion which is not continued is looped or knotted so as to prevent its passage back through the opening 25.

The melody is played on the strings 30 by means of a bow or similar instrument. It is apparent that since the studs are mounted so as to gradually increase in height and since the strings are directed around the rear side thereof, the bow may be very expeditiously advanced from one note to another by sliding across the rounded portions of the strings which is indicated by 34 in the drawings. At the same time the bow is moved across the strings 30, the strings 15 may be manipulated so as to produce an accompanying melody. Since half notes can be obtained from the above construction, it is apparent that we have greatly increased the range of the instrument.

In Fig. 6 we have depicted the modified form of construction for our invention wherein we form the members 16 and 17 so as to embody a taper on the upper side thereof which is disposed so that the incline thereof is toward the adjustable anchor elements as indicated by 35 in the drawings. In this construction the anchoring elements are all run into the supporting members 16 and 17 an equal amount and therefore due to the taper on the upper side thereof, these anchoring elements will automatically be disposed in gradually increasing heights so as to facilitate the shifting of the bow from one string to another.

It is apparent from the foregoing that we have provided a construction wherein a comparatively large range of notes may be obtained and inasmuch as we employ but a single string which is securely snubbed and which embodies branch portions which may be individually tuned, it is apparent that we have obtained a very simple construction which will be economical in manufacture.

While we have illustrated and described the preferred form of construction for car-

rying our invention into effect, this is capable of variation and modification, without departing from the spirit of the invention. We therefore, do not wish to be limited to the 5 precise details of construction set forth but desire to avail ourselves of such variations and modifications as come within the scope of the appended claims.

Having thus described our invention, what 10 we claim as new and desire to protect by Letters Patent is:

1. In a stringed musical instrument, a plurality of strings of substantially **U**-shaped formation, means for anchoring said strings 15 in the bight portions thereof, and means for anchoring the other ends of said strings including frets and adjustable tuning posts whereby said strings may be individually tuned.

2. In a stringed musical instrument, a plurality of substantially **U**-shaped strings, means for securing the free ends of said strings including frets and tuning posts to which said strings are individually connected, 25 means for securing said strings at the bight portions thereof including anchoring elements disposed in rows, said anchoring elements being arranged so as to be of gradually increasing height along said rows, the 30 anchoring elements of greatest height being disposed toward said frets, said anchoring elements being arranged such that said strings may be directed theraround and secured thereto in such a manner that said 35 strings will pass downwardly along said anchoring elements on the side thereof disposed toward the juxtaposed element of lesser height.

3. In a stringed musical instrument, a 40 sound box, supporting members mounted on the upper end of said sound box in substantially **V**-shaped formation, anchoring elements disposed on the upper side of said supporting members in aligned rows, means for 45 connecting the ends of said supporting members opposite the joining ends thereof, adjustable anchoring elements mounted on said means, other adjustable anchoring elements mounted on the sides of said supporting members, frets mounted in juxtaposition to said 50 adjustable anchoring elements and disposed toward said first named anchoring elements, a plurality of substantially **U**-shaped strings adapted to have the bight portions thereof 55 connected to said first named anchoring elements and adapted to have one of the branch portions thereof secured to said first named adjustable anchoring elements while the other branch portions thereof are connected to said 60 second mentioned adjustable anchoring elements.

In testimony whereof we affix our signatures.

LEONARD DODSON.
JAMES DODSON.
